UNITED STATES PATENT OFFICE.

HERMAN BOCK, OF MILWAUKEE, WISCONSIN, ASSIGNOR OF ONE-HALF TO JOHN SANDER, OF MILWAUKEE, WISCONSIN.

TRAFFIC SIGNAL.

Application filed November 8, 1921. Serial No. 513,663.

To all whom it may concern:

Be it known that I, HERMAN BOCK, a citizen of the United States, and resident of Milwaukee, in the county of Milwaukee and State of Wisconsin, have invented certain new and useful Improvements in Traffic Signals; and I do hereby declare that the following is a full, clear, and exact description thereof.

10 My invention relates to a new and improved traffic signal and its primary object is to provide a device of this character which may be automatically operated from the city lighting circuit or by other motive power so as to direct the traffic at a crossing without necessitating the presence of a traffic policeman.

15 A further important object of the invention is to provide means by which to vary the interval of time during which successive signals are displayed in proportion to the density of traffic which passes the crossing in each direction.

20 The structure and operation of my improved signal will be better understood from the following detailed description in which reference is made to the accompanying drawings, in which:—

25 Figure 1 is a front elevational view of my invention.

30 Figure 2 is a plan view of the same with a portion of the casing cut away in order to show the operating mechanism.

35 Figure 3 is a vertical sectional view thru the operating mechanism and casing in which it is supported.

40 Referring more specifically to the drawings the numeral 5 indicates a supporting base or pedestal having a hollow cylindrical upper portion 6 which is provided with windows 7 facing in the directions from which the traffic approaches. This upper portion is provided with a suitable overhanging cover 8 and with a bottom 9. A bearing 10 is provided in which is journaled the upper end of a vertical shaft 11, the lower end of the shaft resting in the thrust bearing 12 secured to the bottom 9. A cylindrical casing 13 is carried by the shaft 11 and suitably braced by a spider 14. The casing is opaque except for the transparent portions 15 through which the traffic signals "Go" and "Stop" are displayed by means of a light within the casing. A motor 16 which may be connected with the lighting

45 circuit or operated in any other suitable manner is mounted within the casing and connected by back gearing 17 to a vertical stub shaft 18 which is suitably supported by means of the bracket 19. A pair of arms 50 20 and 21 are mounted on the stub shaft and each arm is provided with a lug 22 which as the stub shaft and arms revolve successively engage the teeth of a toothed wheel 23 which is carried by a stub shaft 24. The 55 toothed wheel is connected with a spur gear 25 which drives a pinion 26 which is secured to the vertical shaft 11.

60 The gearing is so proportioned that when one of the lugs 22 engages one of the teeth 70 of the wheel 23 the shaft 11 and the cylindrical casing 13 will be rotated through an arc of 90°, thus reversing the traffic signals and permitting traffic to pass transversely to the direction in which it has been previously 75 passing. It will be appreciated that at many crossings the traffic along one street is considerably denser than the traffic transverse thereto. For this reason I have made the arm 21 adjustable angularly about the 80 shaft 18 by providing the set screw 27. By this means the angle between the arms 20 and 21 may be suitably adjusted and it will be understood that the relative time during 85 which traffic is permitted to proceed in each direction will be exactly proportional to the arcs subtended by the arms 20 and 21. Thus the relative time for displaying each of the signals may be regulated in accordance with the traffic. The back gearing 17 may be 90 arranged with any desired ratio so as to make the cycle of the traffic signals of any length of time desired.

95 While I have described and shown specifically one structure by means of which the principle of my invention may be carried out it will be understood that various modifications may be made therein, without departing from the scope of the invention as claimed.

100 I claim as my invention:

1. A traffic signal comprising a revolvably mounted indicating member, rotary mechanism permanently connected thereto, and including a toothed wheel, a pair of relatively adjustable revolvably mounted members each of which has a single operative portion adapted to intermittently engage said toothed wheel, and driving mechanism for said pair of members.

2. A device of the character described comprising a casing through which traffic signals may be displayed, a vertical rotatable shaft on which the casing is mounted, 5 a toothed wheel geared to the shaft, a motor mounted within the casing, a vertical stub shaft back geared to the motor and having a pair of arms secured thereto, each of said arms during their revolution, being intermittently engageable with said toothed

wheel to rotate said casing through an arc of ninety degrees, and means for adjusting the angle between said arms, for the purpose set forth.

In testimony that I claim the foregoing I 15 have hereunto set my hand at Milwaukee, in the county of Milwaukee and State of Wisconsin.

HERMAN BOCK.
